UNITED STATES PATENT OFFICE.

SIDNEY A. KELLER, OF NEW YORK, N. Y., ASSIGNOR TO MARCUS T.
GOLDSMITH, OF NEW YORK, N. Y.

DESIGN FOR A HAND-MIRROR OR SIMILAR ARTICLE.

No. 37,723.

Specification for Design.

Patented Dec. 12, 1905.

Application filed October 31, 1905. Serial No. 285,350. Term of patent 7 years.

To all whom it may concern:

Be it known that I, SIDNEY A. KELLER, a citizen of the United States, and a resident of the city of New York, borough of Manhattan, in the county and State of New York, have invented a new, original, and ornamental Design for a Hand-Mirror or Similar Article, reference being had to the accompanying drawings, in which—

Figure 1 is a front face view of a hand-mirror, showing my design; and Fig. 2 is a rear face view of the same.

I claim—

The ornamental design for a hand-mirror or similar article, as shown.

SIDNEY A. KELLER.
